Primary Examiner — Jonathan J Han

CLAIM

The ornamental design for a sole, as shown and described.

DESCRIPTION

FIG. 1 is a top rear perspective view of a sole, showing my new design;

FIG. 2 is a bottom rear perspective view thereof;

FIG. 3 is an enlarged front view thereof;

FIG. 4 is an enlarged rear view thereof;

FIG. 5 is a left side view thereof;

FIG. 6 is a right side view thereof;

FIG. 7 is a top view thereof; and,

FIG. 8 is a bottom view thereof.

1 Claim, 8 Drawing Sheets
